UNITED STATES PATENT OFFICE.

ALFRED H. OELKERS, OF CHICAGO, ILLINOIS, ASSIGNOR TO AMERICAN STEEL
FOUNDRIES, OF CHICAGO, ILLINOIS, A CORPORATION OF NEW JERSEY.

DRAFT GEAR.

Application filed November 22, 1926. Serial No. 149,811.

My invention relates to a draft appliance for railroad rolling stock, and more particularly to a draft gear adapted to be installed and used with the standard A. R. A. car sill 5 and one which employs an improved wedge gear to aid in taking up the movement instant to blows occasioned in coupling and pulling cars.

In the earliest developments in railway 10 draft gears that employed frictional resisting elements, it was the practice to employ wedge means positioned between and housed within two longitudinal beams positioned under the car that constituted the car sill. As the 15 need for an increased capacity in railroad cars grew and with the development of improved locomotives with larger pulling capacity, the need for a draft gear with an increased capacity was also occasioned. The 20 standard car designs provide for a specific type of car sill with a definite space between the beams thereof, which prevented satisfaction of this need by merely increasing the size of the devices used at that time. If 25 such a practice was followed, the car sills would have necessarily been increased to a size unduly large and expensive and out of proportion to the other uses for the sills in car construction. In answer to this problem, devices have been devised which have 30 an increased frictional capacity and of a design that is readily contained between and housed within the longitudinal beams constituting the car sill.

In order that these qualities may be embodied in a device having these characteristics, it has been necessary to provide a plurality of broken up friction surfaces having compound wedging actions; that is, to provide 40 one wedging face bearing against and adapted to displace a wedging block having more than two wedging faces, for instance, a triangular block, which is displaced bodily by overcoming a second frictional resistance 45 and in its displacing movement in turn displaces a third wedging element resisted by a spring or like means. This type of device has been successful to a greater or less degree but it has been found to be inoperative 50 unless certain limiting specifications are followed which influence materially the substances that may be used, and the consequent cost and the utility of the device. It has been found that when one friction element

bears on another at a predetermined pressure 55 and with a definite wedging angle operating to displace one or the other of these elements in the course of movement, that due to the angle of repose determined by the co-efficient of friction of the two surfaces in contact, 60 that a marked limitation is placed on the angle which may be selected for displacing one of these friction elements by the frictional absorbing movement of the other, without binding of the parts, irrespective of the pressure that may be applied. This situation is very much easier to handle when a wedging element with two friction faces is employed 65 in that the wedging angle, that is, the angle between the two friction faces, may be selected as desired, whereas in the event a triangular wedging member, wedging on three faces, is employed, the angular relationship of the three faces is definitely determined 70 without alteration in that the sum of the angles of the triangle equals 180°. 75

Due to this last condition, devices which have been designed to provide the necessary frictional resistance for cars of increased capacity and to be housed within the beams 80 of the car sill of the standard A. R. A. type, have employed compound frictional means and have been limited in that it has been necessary to vary the materials from which the various parts are made in order to provide 85 frictional faces bearing on three sides of the triangular members which will give a coefficient of friction that will render the device operative notwithstanding the particular angle of repose existing for each one of 90 the cooperating angular surfaces.

To this end, one of the objects of my invention is to overcome these limitations and to provide a more improved draft gear employing frictional wedging members which 95 have only two sides in frictional contact for a single wedge and have sufficient capacity for efficient operation on cars of increased capacity and can be installed for operation in connection with the standard A. R. A. car 100 sill and yet one which is simpler in design and cheaper in construction.

Another object of my invention is to provide a friction draft gear employing the advantages of the above stated objects, which 105 may be assembled through the sides of the sill eliminating the necessity of cutting away the bottom flanges on the sill beams and one

which may be placed under an initial compression after the device has been assembled and to be adjusted from a position outside of the sills to restore the gear to a normal 5 operating condition after wear.

Another object of my invention is to provide a railroad draft appliance comprising a spring gear and a friction gear positioned to operate in series and providing in addition to the usual stops on the sill means, auxiliary stops which are attached to the flanges of the sill beams as well as the webs thereof so that the auxiliary stops abut the spring gear when the draft appliance is in a 10 position of maximum compression to thereby receive and transmit to the flanges of the sill means a portion of the load.

It is another object of my invention to provide a railroad draft appliance comprising a wedge gear made up of two longitudinal wedging elements and two transverse wedging elements having cooperating frictional faces and providing the sill beams with transverse openings through which are 20 positioned the friction draft gears, the wedging members being centrally positioned between the sill beams and extending through and beyond the openings.

Another object of my invention is to provide a railroad draft appliance having a friction gear, the friction faces of which have maximum contacting areas when in an unloaded condition or at an initial position of their operation.

Another object of my invention is to provide a railroad draft appliance having a friction gear and a spring gear operating in series and maintained in abutting relation in their extended position between stop 35 members positioned on the sill beams, in which the wedge gear elements have cooperating stops adapted to contact to limit the extremities of their movement so that the wedge gear will have a predetermined overall dimension at both extremities whereby a decrease in the longitudinal overall dimension occasioned by wear will be taken up by the spring gear.

Another object of my invention is to provide a railroad draft appliance embodying the advantages set forth in the above stated objects, in which the sill beams are provided with openings through which are positioned the wedging members of the wedge gear in 50 which an auxiliary stop is provided, the stop having a U-shaped configuration and is attached to the web and the flange portion of the beam, and is positioned around the margin of the opening in the sill beam in a manner to form a reinforcing member around the cut away portion.

Another object of my invention is to provide a railroad draft appliance having a friction gear of the above described type in 55 which the wedging members are adapted to

be assembled through the sill openings, the longitudinal wedges of which are provided with projections adapted to be positioned between rounded corners of the beam webs when in a maximum separated position so 70 as to prevent lateral displacement when in this position, and the transverse wedges of which are provided with lip portions projecting from the top and bottom thereof in a manner and of proper dimensions to contact the margins of the web surrounding the opening to prevent the transverse wedge members from being inserted too far within the housing formed by the spaced sill beams.

These and other objects are accomplished 75 by means of the arrangement disclosed on the accompanying sheet of drawings, in which—

Figure 1 is a plan view in cross section of a railroad draft appliance constructed in accordance with my invention;

Figure 2 is an elevation in cross section cut on the center line of Figure 1;

Figure 3 is a plan view partly in cross section showing the parts of the draft gear in compression, the parts assuming this position under maximum load; and

Figure 4 is a cross sectional elevation as seen from one end, taken on line 4^x—4^x of 90 Figure 1.

The various novel features of the invention will be apparent from the following description and drawings and will be particularly pointed out in the appended 100 claims.

Referring to the drawings, it will be noted that my device is adapted to be used in connection with the standard A. R. A. car sill, consisting of two spaced beams 10 having flanged portions 11 and vertical web portions 12. Positioned between the beams is a standard form of casting 13 which, among other things, constitutes the stop elements 14 serving as a limiting means for the draft appliance and for transmitting the load from the draft gear to the car sill, the casting member 13 being attached to the webs 12 of the beams by rivets or other suitable means, not shown. Spaced from the stops 14 are 105 similar stops 15 likewise attached to the webs of the beams which serve to transmit the load from the draft gear to the webs of the beams in the opposite direction of movement. It will be further noted that my draft gear consists broadly of a spring gear designated generally as 16 and a friction gear designated generally as 17, these two gears being positioned between the stops 14 and 15 in a manner to operate in series 110 and to abut the stops 14 and 15 respectively when in their maximum extended position or in an unloaded condition. The spring gear 16 consists of a follower 18 having extensions 19 projecting laterally from the sides thereof and a skirt portion 20 which forms 115 120 125 130

a housing for a coil spring 21. The wedge gear 17 is made up of four wedging members, two longitudinal wedges 22, 23 and a transverse floating wedging unit 24, this last named wedging unit comprising two transverse wedge members 25 and 26, each having two wedging faces cooperating with the two wedging faces of each of the two longitudinal wedge members and being further mounted on a rod 27 positioned through openings 28 and 29 respectively through the two transverse wedge members and extending beyond the sides thereof.

Each of the web portions 12 of the beams 10 is provided with an opening 30 of a size to receive each of the four wedging members, it being noted that in final assembled position, as shown in Figure 1, the wedging members are of such a size that while positioned centrally between the two beams, they extend through the opening and beyond the sills thereby presenting frictional faces of increased areas. Positioned on the ends of the rod 27 are coil compression springs 31 and auxiliary springs 32 maintained under compression by the cap 33 and nut 34 threaded as at 35 on the end of the rod 27 so as to provide the wedging unit previously referred to as 24, the inner faces of the transverse wedging members 25 and 26 contacting as at 36 when the draft gear is in unloaded condition. The longitudinal wedging member 22 is adapted to receive the yoke 37 which is in turn connected by the pin 38, shown in Figure 2, to the coupler of the railroad car so that when the draft gear is subjected to a pulling load, the load is transmitted from the yoke member through the wedging gear and through the spring gear to the stops 15 connected to the beams of the car sill.

Between the flanges 19 of the spring gear and the wedging gear, auxiliary stops 39 are provided which are attached by suitable means, such as rivets 40, to the web portion 12 and the flange portion 11 of the sill beams. The auxiliary stops 39 are of a general U-shaped formation and are adapted in their attached positions to surround the opening 30 in the web 12 so as to form a strengthening member around the margins of the opening. The web members 22 and 23 are provided with stops 41 (see Figure 3) which are adapted to engage in a maximum loaded condition of the gear so as to limit the approach of these two wedge members and to form a means for transmitting directly through these two wedge members, independent of the friction surfaces, the load occasioned by pulling or pushing of the railroad car directly to the stop members 14 or 15, as the case may be.

In assembling the friction gear, the yoke together with the spring gear comprising the follower 18 and the spring 21, are inserted

up from the bottom between the inner flanges 11 which may be intact or cut away as desired, and the friction wedges are inserted from the sides through the openings 30 in the web portions 12 of the sill beams, the 70 wedges being inserted through the arms of the yoke after the yoke has been lifted to a height sufficient to permit the wedges to be inserted therethrough. The two longitudinal wedges 22 and 23 are inserted first and 75 are moved to their maximum separated positions, in which position the shoulders 42, which are squared as shown in Figure 2, project behind the rounded corners 43 of the opening so as to prevent lateral displacement 80 during the assembling operation. When in this position, the two transverse wedge members 25 and 26 are inserted between the longitudinal wedges from their respective sides until their friction faces contact with the 85 frictional faces of the longitudinal wedge members at which time the rod 27 is inserted through the center openings and the springs positioned on the outer ends thereof. The transverse wedges are further provided with 90 upper and lower lugs 48 on their upper and lower surfaces adjacent the outer edge to prevent them from being inserted too far inwardly between the sill beams when they are projected through the openings 30, the lugs contacting the marginal portion of the web 12 of the sill when the wedges are 95 slightly beyond the center line. In the position shown in Figure 1, a slight clearance is provided between the lugs and the web.

In order to compress the spring members 31 and 32 an extent sufficient to permit the cap 33 and nut 34 to be attached to the end of the rod, openings 44 are provided in the outer faces of the wedge members adapted to receive bolts 45 which are temporarily inserted and together with the yoke 46 and the nuts 47 form means for placing the springs under compression an amount sufficient to permit the cap 33 and the nut 34 to be attached. After the nut 34 is in threaded relation with the rod 27, the bolts 45 and the yoke 46 may be removed and the initial compression of the parts of the draft gear may be effected by adjusting the nut 34. The yoke member 37 connected with the car coupler is adapted to abut the outer portion 49 of the follower 18 so that the draft gear may be put under compression under a pushing load as well as a pulling load, in which case the stops 14 serve to transmit the load taken through the draft gear to the webs 12 of the beams up until the device is in a condition of maximum compression, at which time the projections 19 on the follower 18 contact the auxiliary stops 39 for partially absorbing the maximum load in this direction, the stops 39 serving to transmit a part of the load imparted to them to the flanges 11 of the beams and in this manner relieve the webs 12 of

excessive strains which would tend to buckle and damage the beams. It is to be noted that the auxiliary stops are needed in the direction of the pushing load in that the draft gear assumes a position of maximum compression only when subjected to unusual blows as occasioned in coupling cars, and that the draft gear does not assume a completely compressed position under ordinary pulling conditions of a loaded train.

In operation, when the parts are assembled, the wedges are inserted through the sides as above stated, the initial compression of the spring 21 of the spring gear being effected by tightening of the springs 31 and 32 of the transverse wedge member by means of the nut 34. The wedging resistance is so selected relative to the necessary load for compressing the spring 21 that the wedging gear as a unit will remain inoperative until the spring 21 is compressed an amount sufficient to bring the longitudinal wedge 23 in contact with the skirt portion 16 of the follower 18, at which time the wedging unit comes into operation. By selecting the type of wedge members herein disclosed, a degree of flexibility is provided in selecting the angle between the cooperating wedges, namely, the longitudinal wedges and the transverse wedges, which permits the wedges to be constructed of the same material, and further, in providing wedges of increased size assembled through and projecting beyond the webs of the beams, frictional surfaces of unlimited area may be employed without changing the form of the standard A. R. A. car sills.

One of the important features in the operation of my invention resides in the fact that the cooperating frictional faces between the wedges 25 and 26 and 22 and 23 are in contact with a maximum area when in an unloaded condition, and that under operating movement, the frictional faces slide in overlapped relation, as shown in Figure 3. This feature is important for the reason that the maximum frictional movement between the parts is occasioned at the starting position or from the position shown in Figure 1, due to the fact that blows of small degree occur more frequently than excessive blows, therefore, by having the frictional faces in contact throughout their entire surface initially, a uniform wearing away of the cooperating surface is provided, eliminating the formation of pockets or worn spots in the faces with the consequent formation of an objectionable ridge, it being found in practice that the formation of ridges due to excessive worn spots frequently results in producing a condition of inoperativeness in the draft gear.

I claim:

1. In a railroad draft appliance, a car sill comprising a pair of spaced beams having openings through their web portions, a fric-

tion gear comprising two lateral wedges and two longitudinal wedges positioned between and extending beyond said beams through said openings, said wedges having friction surfaces initially in contact throughout their 70 entire working areas.

2. In a railroad draft appliance, a car sill comprising a pair of spaced beams having openings through their web portions, a friction gear positioned between and extending 75 beyond said beams through said openings, said gear having friction surfaces initially in contact throughout their entire working areas.

3. In a railroad draft appliance, a car sill 80 comprising a pair of spaced beams having openings through their web portions, a friction gear positioned between and extending beyond said beams through said openings, said gear having contacting frictional surfaces of a maximum area when in an 85 unloaded condition.

4. In a railroad draft appliance, a car sill comprising a pair of spaced beams having openings through their web portions, a friction gear positioned between and extending beyond said beams through said openings, said gear having contacting frictional surfaces of a maximum area at the beginning 90 of operative movement and diminishing 95 with an increase in movement under load.

5. In a railroad draft appliance, the combination of a car sill and a friction gear, said sill comprising a pair of spaced beams having openings therethrough, said friction gear comprising two longitudinal wedges centrally spaced between said beams and projecting through and beyond said openings and a pair of transverse wedges contacting at the center line of said sill and extending 100 through and beyond said openings, and means for yieldingly maintaining said wedges in operative engagement.

6. In a railroad draft appliance, the combination of a car sill and a friction gear, 110 said sill comprising a pair of spaced beams having openings therethrough, said friction gear comprising two longitudinal wedges centrally spaced between said beams and projecting through and beyond said openings and a pair of transverse wedges engaging said longitudinal wedges and extending through and beyond said openings, and means for yieldingly maintaining said 115 wedges in operative engagement.

7. In a railroad draft appliance, the combination of a car sill and a friction gear, said sill comprising a pair of spaced beams having openings therethrough, said friction gear comprising two longitudinal wedges centrally spaced between said beams and projecting through and beyond said openings and a pair of transverse wedges engaging said longitudinal wedges initially 125 with maximum contacting surfaces and ex- 130

tending through and beyond said openings, and means for yieldingly maintaining said wedges in operative engagement.

8. In a railroad draft appliance, the combination of a car sill and a friction gear, said sill comprising a pair of spaced beams having openings therethrough, said friction gear comprising two opposed longitudinal wedge members resiliently maintained between stop means on said sill, and a floating transverse wedging unit positioned between said longitudinal wedges comprising a pair of opposed initially abutting wedges mounted on a rod, spring means mounted on said rod abutting said transverse wedges and means on said rod for retaining said spring means and effecting an initial compression thereof, all of said wedge members extending through and beyond said openings.

9. In a railroad draft appliance, the combination of a car sill and a friction gear, said sill comprising a pair of spaced beams having openings therethrough, said friction gear comprising two opposed longitudinal wedge members and a floating transverse wedging unit positioned between said longitudinal wedges comprising a pair of opposed initially abutting wedges mounted on a rod, spring means mounted on said rod abutting said transverse wedges, and means on said rod for retaining said spring means, all of said wedge members extending through and beyond said openings.

10. In a railroad draft appliance, the combination of a car sill having two spaced stops, a longitudinal spring abutting one of said stops and two longitudinal wedge members positioned between and abutting said spring and the other of said stops, two transverse wedge members positioned between said longitudinal wedge members and being mounted on a rod having springs causing compression of said wedges and longitudinal springs, said wedge members and said rod projecting laterally through and beyond said sill and having means for adjusting said springs whereby an initial compression can be readily effected by adjusting said last named springs.

11. In a railroad draft appliance, the combination of a car sill and a spring gear and a wedge gear positioned to operate in series, said draft gear comprising two longitudinal wedge members and two transverse wedge members, said transverse wedge members being mounted on a rod having springs and spring adjusting means thereon, said wedges, springs and spring adjusting means projecting through and beyond said sills whereby an initial compressing of said parts may be readily effected after said parts are assembled.

12. In a railroad draft appliance, the combination of a car sill comprising spaced beams having web portions and inwardly

extending flange portions, a spring gear and a friction and wedge gear positioned to operate in series, stops on said web portions abutting said gears in their extended position, and auxiliary stops attached to said web portions and said flange portions for abutting said spring gear when said gears are under maximum compression in buff whereby part of the load is transmitted through said auxiliary stops to said web portions and said flange portions.

13. In a railroad draft appliance, the combination of a car sill comprising spaced beams having web portions and inwardly extending flange portions and a draft gear, stops on said web portions abutting said gear when in extended position, and auxiliary stops attached to said web portions and said flange portions for abutting said gear when under maximum compression in buff whereby part of said load is transmitted through said auxiliary stops to said web portions and said flange portions.

14. In a railroad draft appliance, the combination of a car sill comprising spaced beams having openings therethrough, a draft gear positioned centrally of said beams extending through and projecting beyond said openings, an auxiliary stop for said gear attached to said beams shaped in a manner and positioned so as to form a reinforcing means for the margin of said openings.

15. In a railroad draft appliance, the combination of a car sill, a wedge gear, a spring gear, and auxiliary stops on said car sill, said wedge gear comprising a pair of opposed longitudinal wedges and a pair of transverse spring pressed wedges cooperating therewith, said longitudinal wedges being provided with stops adapted to contact after a predetermined amount of compression in buff movement of said wedge and spring gears said predetermined amount causing said spring gear to abut said auxiliary stop.

16. In a railroad draft appliance, the combination of a car sill comprising spaced beams having openings therethrough and a wedge gear comprising cooperating wedges, said gear being positioned centrally of said beams and extending through and beyond said openings and means for yieldingly maintaining said wedges in operative engagement, two of said wedges being longitudinally disposed and portions projecting between portions of said beams when in maximum separated position whereby lateral displacement in this position is prevented.

17. In a railroad draft appliance, the combination of a car sill comprising spaced beams having openings therethrough, and a spring gear and a wedge gear positioned centrally between said beams in a manner to operate in series, said beams having stops

- for abutting said spring gear and wedge gear respectively in extended position, and an auxiliary stop for abutting said spring gear in the position of maximum compression, said wedge gear comprising a pair of longitudinal wedges positioned between one of said stops and said spring gear, and a pair of spring pressed transverse wedges positioned between and cooperating with 5 said longitudinal wedges, both of said pairs of wedges extending through and beyond said openings and being provided with stop portions for cooperating respectively at the opposite extremities of movement whereby 10 said wedge gear will have a predetermined overall dimension in both extremities of movement to cause the transverse wedges to contact at the same time the spring gear and wedge gear contact said stop in extended 15 position and to cause the longitudinal wedges to contact at the same time the spring gear contacts said auxiliary stop.
18. In a railroad draft appliance, the combination of a car sill comprising spaced 20 beams having openings therethrough, and a wedge gear comprising a pair of longitudinal wedges and a pair of transverse wedges, and means for yieldingly maintaining said 25 wedges in operative engagement, said transverse wedges contacting centrally between said beam and having portions positioned outside of said beams, said last named portions being provided with projections for 30 contacting the beam adjacent the margin of said opening whereby said wedges are prevented from being inserted too far.
19. In a railroad draft appliance, the combination of a car sill comprising spaced 35 beams having openings therethrough, and a wedge gear positioned centrally of said beams, projecting through said openings and extending beyond said sills, said openings and wedge members being of a size to permit the wedge gear to be assembled through said 40 openings.
20. In a railroad draft appliance, the combination of a car sill comprising spaced 45 beams having openings therethrough, and a wedge gear positioned centrally of said beams, projecting through said openings and extending beyond said sills, said openings and wedge members being of a size to permit the wedge gear to be assembled through and to operate while projecting through said 50 openings.
21. In a railroad draft appliance, the combination of a car sill comprising spaced

beams having openings through their web portions, and a friction draft gear, frictional elements of which are assembled 60 through said openings, said draft gear in assembled relation extending beyond the edges of said opening and having means for limiting inward movement therethrough whereby said draft gear is held against lateral displacement. 65

22. In a railroad draft appliance, the combination of a car sill comprising spaced beams having openings through their web portions, and a friction draft gear, frictional 70 elements of which are assembled through and extend beyond said openings, said spaced beams having means attached thereto extending above said openings and forming supports for said draft gear. 75

23. In a railroad draft appliance, the combination of a car sill comprising spaced beams, said beams having web portions and flange portions, and a friction draft gear, said web portions having openings through 80 which frictional elements of said draft gear are assembled and extend beyond, and means attached to said flange portions extending above the edges of said openings forming supports for said draft gear. 85

24. In a railroad draft appliance, the combination of a car sill comprising spaced beams having transversely aligned openings in their web portions, means attached to said beams for reinforcing the edges of said 90 openings, and a draft gear having friction elements extending through said openings and extending beyond the sides of said beams and resting on said means reinforcing the edges of said openings. 95

25. In a railroad draft appliance, the combination of a car sill, a friction gear projecting through and beyond said sills, and an auxiliary stop attached to the beams of said car sill, said auxiliary stop being provided 100 with portions underlying said friction gear for supporting said friction gear.

26. In a railroad draft appliance, the combination of a car sill having openings through the beams thereof, a friction gear 105 projecting through and beyond said openings and an auxiliary stop attached to said car sill, said stop being constructed to form a reinforce for said openings and to present portions underlying said friction gear for 110 supporting said friction gear.

Signed at Chicago, Illinois, this 18th day of November, 1926.

ALFRED H. OELKERS.
